UNITED STATES PATENT OFFICE.

HAROLD HIBBERT, OF WILMINGTON, DELAWARE, ASSIGNOR TO E. I. DU PONT DE NEMOURS POWDER COMPANY, OF WILMINGTON, DELAWARE, A CORPORATION OF NEW JERSEY.

PROCESS FOR THE SYNTHESIS OF ORGANIC CONDENSATION PRODUCTS.

1,261,811.

Specification of Letters Patent.

Patented Apr. 9, 1918.

No Drawing.

Application filed November 28, 1913. Serial No. 803,436.

To all whom it may concern:

Be it known that I, HAROLD HIBBERT, of Wilmington, in the county of New Castle and in the State of Delaware, have invented a 5 certain new and useful Improvement in Processes for the Synthesis of Organic Condensation Products, and do hereby declare that the following is a full, clear, and exact description thereof.

10 My invention relates particularly to the production of condensation products from organic compounds, but it has reference more particularly to the production of condensation products from aldehydes, ketones, 15 etc., and the synthesis of aldols by such condensation.

It has been well known that organic compounds such as aldehydes, ketones, etc., in the presence of alkali or alkaline salts, undergo condensation. For instance, the aldehyde or aldehydes in the presence of an alkaline solution undergoes the condensation known as the aldol condensation; that is to say, two molecules of the aldehyde unite to 25 form an aldehyde alcohol or aldol derivative. In the case of acetaldehyde forming acetaldol, the change would be as follows:

30 A disadvantage of the condensations as previously carried out is that such condensations have been effected in general in an aqueous or alcoholic solution. The process when carried out in this manner is expensive, owing to the cost involved in isolating 35 the pure product. A further disadvantage has been in the formation of resinous products, especially where aqueous solutions have been employed, thus resulting in poor yields.

40 In a recent application of mine, Serial No. 696,342, filed May 10, 1912, I have sought to overcome this difficulty by the action of a solid condensing medium on a mixture of the aldehyde with an inert solvent 45 such, for example, as gasolene, which latter is miscible with the aldehyde but immiscible with the condensation product. When a condensing agent such as caustic soda is used in such a mixture, with acetaldehyde, acet- 50 aldol is formed which is insoluble in gaso- lene and of a higher specific gravity, so that it at once separates out, collecting at the bottom of the vessel so as to be thus readily capable of isolation from the remaining 55 compounds present.

I have discovered that such condensations and especially those carried out in connection with aldehydes, may be effected by the presence of a small quantity of an alkali metal or an alkaline earth metal, either in 60 the isolated state or in the form of a mixture, alloy or amalgam. By the term "metal" I thus mean to include the metal whether in the isolated state or in the form of a mixture, alloy or amalgam. In producing the condensation in this manner, no 65 solvent is required, although a solvent may be used, if desired, without interfering with the course of the reaction. Furthermore, I have found that in some instances an alcohol 70 or similar liquid forming an alkaline salt, may be added when found desirable, although this is not necessary.

My invention may be carried out in many 75 different ways but for the purpose of illustration I may proceed as follows: 200 grams of freshly distilled and preferably practically anhydrous acetaldehyde are cooled preferably to about -6° C. with a freezing mixture, and then about 0.15 grams of finely 80 divided sodium are added. The contents are then preferably shaken every few minutes for about an hour, keeping the temperature preferably below 5° C., and then for another sixteen or eighteen hours at preferably 85 0° C. During the process, the sodium completely disappears. After neutralization, by the addition of a saturated solution of sodium bisulfate, for example, and distilling off the unchanged acetaldehyde, a 90 very pure acetaldol remains behind.

While in the above example I employ 0.15 grams of sodium, I do not wish to limit myself to this amount since much larger quantities may be employed. The best results 95 are obtained, by using not more than 0.5% of sodium, calculated on the weight of acetaldehyde taken.

I have found that the sodium may be substituted by an amalgam of sodium or any 100 other alkali or alkaline earth metal, so as to obtain equally satisfactory results. An example of this may be the following: 100 grams of freshly distilled and practically anhydrous acetaldehyde are cooled to preferably -9° C. and 16 grams of a sodium amalgam containing about 1% of sodium are added. These materials are kept in a freezing mixture and are preferably well shaken from time to time in order to pre- 105 110

vent a too rapid rise in temperature. After about two hours, the temperature of the materials is permitted to rise to preferably 8° C. and is kept at this temperature with an occasional shaking for a period of preferably sixteen hours. After neutralization by the addition of a saturated solution of sodium bisulfate and distilling off the unchanged acetaldehyde, a very good yield of 10 very pure acetaldol remains.

As previously indicated, the reaction may be varied, if desired, by the addition of a little alcohol. This may be added prior to the addition of the condensing agent. An 15 example of the process as carried out in this manner may be as follows: 100 grams of acetaldehyde are mixed with 6 cc. of practically anhydrous ethyl alcohol and the mixture cooled to about -8° C. 16 grams of a 20 sodium amalgam containing about 1% sodium are then introduced, the materials being kept preferably in a freezing mixture and shaken in order to avoid any undue rise of temperature. After about one hour, the materials are transferred from the freezing mixture to ice water so as to maintain the temperature around approximately 0° C. for about sixteen hours. After neutralization by the addition of an aqueous sodium bisulfate solution, the excess of acetaldehyde is removed by distillation, thereby leaving behind as a residue very pure acetaldol. I have found that in the above example instead of alcohol any other liquid capable of 35 forming an alkaline salt may be employed. Furthermore, it is to be understood that if desired the procedure may be varied by carrying out the condensation in a cooled mixture of practically anhydrous aldehyde with 40 some inert solvent miscible with the aldehyde but immiscible with the condensation product, such as gasoline.

While I have described my invention above in detail, I wish it to be understood 45 that many changes may be made therein without departing from the spirit of my invention.

I claim:

1. The process of condensation which 50 comprises subjecting an organic compound containing a carbon atom and an oxygen atom united by a double bond of union to the action of an alkali-forming metal in the presence of a substantially anhydrous liquid organic compound capable of forming a salt with an alkali-forming metal.

2. The process of condensation which 60 comprises subjecting an organic compound containing a carbon atom and an oxygen atom united by a double bond of union, to the action of an alkali metal in the presence of a substantially anhydrous liquid organic compound capable of forming a salt with an alkali metal.

3. The process of condensation which 65

comprises subjecting an organic compound containing a carbon atom and an oxygen atom united by a double bond of union, to the action of sodium in the presence of a substantially anhydrous liquid organic compound 70 capable of forming a salt with sodium.

4. The process of condensation which comprises subjecting an aldehyde to the action of an alkali-forming metal in the presence of a substantially anhydrous liquid organic 75 compound capable of forming a salt with an alkali-forming metal.

5. The process of condensation which comprises subjecting an aldehyde to the action of an alkali metal in the presence of a substantially anhydrous liquid organic compound 80 capable of forming a salt with an alkali metal.

6. The process of condensation which comprises subjecting an aldehyde to the action 85 of sodium in the presence of a substantially anhydrous liquid organic compound capable of forming a salt with sodium.

7. The process of condensation which comprises subjecting acetaldehyde to the action 90 of an alkali-forming metal in the presence of a substantially anhydrous liquid organic compound capable of forming a salt with an alkali-forming metal.

8. The process of condensation which comprises subjecting acetaldehyde to the action 95 of an alkali metal in the presence of a substantially anhydrous liquid organic compound capable of forming a salt with an alkali metal.

9. The process of condensation which comprises subjecting acetaldehyde to the action 100 of sodium in the presence of a substantially anhydrous liquid organic compound capable of forming a salt with sodium.

10. The process of condensation which comprises subjecting an organic compound containing a carbon atom and an oxygen atom united by a double bond of union, to the action of an alkali-forming metal, in a 110 mixture of the organic compound with a solvent which is miscible with the organic compound but immiscible with the condensation product in the presence of a substantially anhydrous liquid organic compound 115 capable of forming a salt with an alkali-forming metal.

11. The process of condensation which comprises subjecting an organic compound containing a carbon atom and an oxygen atom united by a double bond of union, to the action of an alkali metal, in a mixture of the organic compound with a solvent which is miscible with the organic compound but immiscible with the condensation products in the presence of a substantially anhydrous liquid organic compound capable 120 of forming a salt with an alkali-forming metal.

12. The process of condensation which 125

- comprises subjecting an organic compound containing a carbon atom and an oxygen atom united by a double bond of union, to the action of the sodium, in a mixture of the 5 organic compound with a solvent which is miscible with the organic compound but immiscible with the condensation product in the presence of a substantially anhydrous liquid organic compound capable of forming 10 a salt with sodium.
13. The process of condensation which comprises subjecting an aldehyde to the action of an alkali-forming metal, in a mixture of the aldehyde with a solvent which 15 is miscible with the aldehyde but immiscible with the condensation product in the presence of a substantially anhydrous liquid organic compound capable of forming a salt with an alkali-forming metal.
- 20 14. The process of condensation which comprises subjecting an aldehyde to the action of an alkali metal, in a mixture of the aldehyde with a solvent which is miscible with the aldehyde but immiscible with the 25 condensation product in the presence of a substantially anhydrous liquid organic compound capable of forming a salt with an alkali-forming metal.
15. The process of condensation which 30 comprises subjecting an aldehyde to the action of sodium, in a mixture of the aldehyde with a solvent which is miscible with the aldehyde but immiscible with the condensation product in the presence of a substantially anhydrous liquid organic compound capable of forming a salt with sodium.
16. The process of condensation which 35 comprises subjecting acetaldehyde to the action of an alkali-forming metal, in a mixture of the acetaldehyde with a solvent which is miscible with the aldehyde but immiscible with the condensation product in the presence of a substantially anhydrous liquid organic compound capable of forming a salt with an alkali-forming metal.
17. The process of condensation which 40 comprises subjecting acetaldehyde to the action of an alkali metal in a mixture of the acetaldehyde with a solvent which is miscible with the aldehyde but immiscible with the condensation product in the presence of a substantially anhydrous liquid organic compound capable of forming a salt with an alkali-forming metal.
18. The process of condensation which 45 comprises subjecting acetaldehyde to the action of sodium, in a mixture of the acetaldehyde with a solvent which is miscible with the aldehyde but immiscible with the condensation product in the presence of a substantially anhydrous liquid organic compound capable of forming a salt with sodium.
19. The process of condensation which 50 comprises subjecting an organic compound containing a carbon atom and an oxygen atom united by a double bond of union, to the action of an alkali-forming metal, and then neutralizing and distilling off the unchanged organic compound.
20. The process of condensation which 55 comprises subjecting an organic compound containing a carbon atom and an oxygen atom united by a double bond of union, to the action of an alkali metal, and then neutralizing and distilling off the unchanged organic compound.
21. The process of condensation which 60 comprises subjecting an organic compound containing a carbon atom and an oxygen atom united by a double bond of union, to the action of sodium, and then neutralizing and distilling off the unchanged organic compound.
22. The process of condensation which 65 comprises subjecting an aldehyde to the action of an alkali-forming metal, and then neutralizing and distilling off the unchanged aldehyde.
23. The process of condensation which 70 comprises subjecting an aldehyde to the action of an alkali metal, and then neutralizing and distilling off the unchanged aldehyde.
24. The process of condensation which 75 comprises subjecting an aldehyde to the action of sodium, and then neutralizing and distilling off the unchanged aldehyde.
25. The process of condensation which 80 comprises subjecting acetaldehyde to the action of an alkali-forming metal, and then neutralizing and distilling off the unchanged acetaldehyde.
26. The process of condensation which 85 comprises subjecting acetaldehyde to the action of an alkali metal, and then neutralizing and distilling off the unchanged acetaldehyde.
27. The process of condensation which 90 comprises subjecting acetaldehyde to the action of sodium, and then neutralizing and distilling off the unchanged acetaldehyde.
- In testimony that I claim the foregoing I have hereunto set my hand.
- HAROLD HIBBERT.
